UNITED STATES PATENT OFFICE.

ROBERT A. GALLY, OF CINCINNATI, OHIO, ASSIGNOR TO THE BALDWIN COMPANY, OF CINCINNATI, OHIO.

MUSIC-PLAYER VALVE-ACTION.

1,273,846.

Specification of Letters Patent. Patented July 30, 1918.

Application filed September 28, 1917. Serial No. 193,681.

To all whom it may concern:

Be it known that I, ROBERT A. GALLY, a citizen of the United States, and residing at Cincinnati, in the county of Hamilton and State of Ohio, have invented certain new and useful Improvements in Music-Player Valve-Actions, of which the following is a specification.

In this applicant's prior Patent #1,101,919, June 30, 1914, is set forth and claimed a plurality of controlling pneumatics and valves to a single power pneumatic, and the moving board of the power pneumatic adapted to return the stroke valve to its seat. That patent also mentions, page 8, lines 101 to 104, that "the two primary valves can be operated by a single oblong pneumatic arranged to be free to rise at one end in advance of the other." In the present invention two valves are disposed at two distant points of a lever, and a single pneumatic is disposed in operative position to the said lever but intermediate the two said valves, thus enabling successive action of the two valves from the one pneumatic, and a peculiar primary pneumatic is provided so disposed as to return the one or both valves, either from the air of the power pneumatic when the same is opened to the return normal atmospheric pressure air service, or to act at all times. In M. Gally Patent #214,121, April 8, 1879, a pneumatic follower button *a* is adapted to return the valves *g* and *h* after their operation from the outer air through the aperture *B* when opened by the music sheet *N*, but the present invention provides for a return pneumatic actuated from the air from the interior of the striker pneumatic or of constant action. In the drawings Figure 1 is a cross section of a power pneumatic and the novel valve and primary pneumatic arrangement with an intermittent return pneumatic, and Fig. 2 is a similar view of a modified structure with the return pneumatic adapted to constant action.

A striker pneumatic 1 has a moving board 2 and a fixed board 3, the fixed board 3 removably attached to the valve board 4 of the action chest 5. Such attachment is conveniently made by means of a clip or plate 6 fastened to the valve board 4 and having a hole in the upper end of the said clip 6 in which hole a pin 7 is engaged when the pneumatic 1 is in position, the pin 7 being

fast with the heel part of the pneumatic 1. At the front of the chest 5 the valve board 4 is extended farther front than the pouch board 8 of the chest 5, and a screw 9 is passed through the front part of the valve board 4 and into the fixed board 3 of the pneumatic 1, thus holding the pneumatic 1 to the chest 5 but allowing its easy removal when desired.

In the fixed board 3 of the pneumatic 1 is a recess 10 in which the valves 11 and 12 are positioned, somewhat similar to the structure of said prior Patent #1,101,919. The valve 11 controls the connection of the pneumatic 1 to the air chest 5, which chest 5 is understood to be connected to any suitable air suction means, the said valve being normally closed. The valve 12 controls the connection of the pneumatic 1 to the outer air through the channel 13 in the fixed heel part of the pneumatic 1, said valve 12 being normally away from the seat at the inner end of channel 13. These two valves 11, 12, each have an actuating rod 14, 15, the lower end of each said rods being loosely engaged in a hole in a lever 16, one rod near each end of the said lever. Intermediate the two rods 14, 15, a follower button 17 engages the said lever 16 by a rocking joint 18, and a pouch 19 or other suitable pneumatic is positioned to act on the said part of the lever 16 intermediate the two valve rods 14, 15. A duct 20 has the usual tube 21 connecting said duct 20 from the pneumatic socket 22 which controls the action of the pouch 19 and follower button 17, a usual "bleed" return vent 23 serving to allow the return of the pouch 19 and follower 17 at the end of an operation of the valves 11, 12 and the pneumatic 1.

When air is admitted through the tube 21 and duct 20 from any control aperture of a tracker bar, manual valve, or other venting means, the pneumatic socket 22 and its pouch 19 are inflated, thus raising the lever 16. As the valve 11 has the suction load of its port 24, while the valve 12 has practically very little normal suction load, the port under the lower face being small, the valve 12 is lifted by its rod 15 raised by that end of the lever 16, the valve 11 holding down its rod 14 and that end of the lever 16, that end of the lever 16 then being the fulcrum for its movement by the follower 17, which follower 17 and pouch 19

then lift the other end of the lever 16, and the rod 15. When the valve 12 has reached the seat 25 that is above it, that end of the lever 16 that is pressing upward on the rod 15 is stopped from further motion and thus becomes the new fulcrum of that lever 16, whereupon the further rise of the follower 17 will lift the other end of that lever 16, and the rod 14, thus raising the valve 11 and opening the pneumatic 1 to the suction chest 5 through port 24. The pneumatic 1 is then collapsed by the suction of air from the chest 5, and as its moving board 2 is drawn down it starts the action of the spring 26 which is of less dimension than the expanded distance between the moving board 2 and the opposite part of the valve unit 11, as the felt cap 27 on which this spring is mounted, the moving board 2 being brought into contact with the spring 26, thus preparing for a prompt return of the valve 11 when its return movement is started by the collapse of the pouch 19. As the moving board 2 continues its closing movement it increases the compression of the spring 26. The spring 26 may be mounted on the valve unit as shown, or on the moving board 2 as shown in applicant's aforementioned prior Patent #1,101,919, although the present mounting on the cap 27 of the valve 11 makes convenient the removal of the spring at any time.

A check 28 is carried by the moving board 2 in similar manner to that shown in said prior Patent #1,101,919, although the present structure is improved by having the said check 28 engage the cap 27 which rests on valve 11, instead of having that check engage the valve rod 14 as in the said prior patent, the present structure insuring against any tendency to slide the rod 14 down in the valve 11. This check 28 has means for regulation by a screw extending to the outer face of the moving board 2, as in the prior Patent #1,101,919, and it is thus possible to regulate this check 28 so that it will return the valve 11 almost to its seat as the moving board 2 reaches the desired limit of stroke, and at the same time prepares the valve 11 for a very slight motion to reach its seat over port 24 as the pouch 19 is allowed to collapse at the finish of an operation of the device.

A return pouch 29 is placed on the inner face of the valve board 4, its interior being connected to the interior of the striker pneumatic 1 around the rod 15 when the valve 12 is raised at all.

At the normal inactive position and condition of the valves 11 and 12, as shown in Fig. 1, the interior of the striker pneumatic 1 is open to the normal atmospheric pressure outer air, and the valve 12 is seated over the air duct surrounding the rod 15, thus clos-

ing the interior of the return pouch 29 from the outer air of the interior of the striker pneumatic 1. When the tube 21 and duct 20 have been vented to the outer air and the valve 12 starts its rise, the outer air of the 70 interior of the striker pneumatic 1 is connected to the interior of the return pouch 29, and that pouch pulls slightly against the rise of the valve 12, but as there is no suction or other load on the valve 12 during 75 its rising movement, that pull of the return pouch 29 is no detriment, and when the valve 12 reaches the seat 25 and the valve 11 starts to rise and connects the suction of the chest 5 to the interior of the striker pneumatic 1, that same suction is also instantly connected to the interior of the return pouch 29, said return pouch 29 thus being rendered inactive at the same instant that the suction commences to pull down on the 85 valve 12, and thus the return pouch 29 has no action against the holding of the valve 12 to the seat 25 by the pouch 19 at such time and condition of these elements.

When the tube 21 and duct 20 are again 90 closed to the outer air, and the return vent 23 allows the pouch 19 to be collapsed by the pull of the valves 11 and 12 through their rods 14 and 15 and lever 16, the return action of these valves is as follows: The 95 valves 11 and 12 start to return, and the valve 11 usually being held almost entirely closed to its seat over the port 24, reaches a complete closure before the valve 12 has more than just started to leave the seat 25 of outer air channel 13, thus avoiding any "air cut" noise of air passing the seat 25 clear through the port 24. At such moment of initial opening of the valve 12 from the seat 25, the outer air is instantly connected to the interior of the return pouch 29, which return pouch then commences to pull down the rod 15 to aid the quick opening of the seat 25 and outer air channel 13. As the valve 12 reaches its original normal position of rest on the valve board 4, the connection to the interior of the return pouch 29 is again closed, thus rendering the return pouch inactive so that the next initial upward motion of the valve 12 may be easily effected by the pouch 19, and also that during the normal condition of non-operation, no loss of air will be allowed to pass down to and through the pores of the return pouch 29.

If no return pouch 29 were employed, the return action of the valve 12 would not be as quick, and it would require a closer set throw of less efficiency, such two conditions not allowing as rapid repetition as when the 115 return pouch is employed.

The outer air service channel placed in the fixed heel piece 30 which extends inwardly from the hinge 30a of the striker pneumatic 1, is attached to the fixed board 3 of the 130

said pneumatic, the air channel 13 extending inwardly from the heel end of the pneumatic to the downwardly opening port 25 leading to the rear part of the recess 10 of the 5 fixed board 3, which rear part of the recess 10 is underneath the heel piece 30. The upper face of the heel piece 30 is slanted downwardly from the hinge end of the pneumatic 1 in toward the main part of the 10 pneumatic 1, and the rear end of the moving board 2 is hinged to the high outer end of the heel piece 30.

Fig. 2 is a modification of the return pouch idea, the modified form having the 15 return pouch 31 disposed intermediate of the two valve rods 14, 15, and thereby acting on the lever 16 to exert a return force against both the valves 11, 12. As shown in Fig. 2 the return pouch 31 is constantly connected to the outer air, so that it is always active, but unlike a mechanical spring applied to a pneumatic valve, the return pouch 31 has a power always of the same ratio to the valve loads and the main pouch 19 no 25 matter what degree of air tension, and so does the return pouch 29 of Fig. 1.

The intermediately positioned pouch 31 has less power against the rise of each valve 11, 12, than the return pouch 29 acting directly on the rod 15 of valve 12, therefore it is not necessary to make the return pouch 31 so small as the return pouch 29.

To prevent too great a movement of the valve 11, a check 32 is employed at or near 35 the end of the lever 16 adjacent the rod 14 of the said valve 11.

The lever 16 may be guided by suitable guide pins as 33, 34, etc.

What I claim as my invention is:—

40 1. Two valves distant from each other and adapted to be moved in similar directions but not being in the same line of motion; a floating lever and connections extended from one of the said valves to the other of the 45 said valves; and a pneumatic means connected to the said lever means intermediate the said two valves.

50 2. Two valves distant from each other and adapted to be moved in similar directions but not being in the same line of motion; a floating lever and connections extended from one of the said valves to the other of the 55 said valves; and a pneumatic means connected to the said lever means intermediate the said two valves, to operate one of the said valves in advance of the time of motion of the other said valve.

60 3. Two valves disposed at a distance one from the other and each adapted to be moved in a line substantially parallel to that of the other said valve; a floating lever and connections extended from one said valve to the other said valve, the said lever movable in a direction similar to the said lines of 65 motion of the said valves, and a pneumatic

means connected to the said lever intermediate its connections to the said valves, to move the said lever in its said direction of motion.

4. Two valves disposed at a distance one 70 from the other and each adapted to be moved in a line substantially parallel to that of the other said valve; a floating lever and connections extended from one said valve to the other said valve, the said lever movable in a direction similar to the said lines of motion of the said valves, and a pneumatic means connected to the said lever intermediate its connections to the said valves, to move the said lever in its said direction of 75 motion, and to operate one of the said valves in advance of the time of motion of the other said valve.

5. A valve board; two valves disposed adjacent one face of the said board and at a 80 distance from each other; a floating lever disposed beyond the opposite face of the said valve-board; a rod extended from each said valve-board through the said valve board and each said rod connected to a part 85 of the said lever distant from the other said rod; and a pneumatic means connected to the said lever intermediate the two said rods to move the said lever and the two said rods and the two said valves in similar directions. 90

6. A valve board; two valves disposed adjacent one face of the said board and at a 95 distance from each other; a floating lever disposed beyond the opposite face of the said valve-board; a rod extended from each said valve-board through the said valve board and each said rod connected to a part of the said lever distant from the other said rod; and a pneumatic means connected to the said lever intermediate the two said rods to move the said lever and the two said rods and the two said valves in similar directions. 100

7. Two valves, a single pneumatic to move both said valves, but one said valve in advance of the other said valve, and a return pneumatic to assist the return of only one of the said valves. 110

8. Two valves, a single pneumatic to move both said valves, and a return pneumatic to assist the return of only one of the said valves. 115

9. Two valves, a pneumatic to move both said valves, and a return pneumatic and mechanical connections from said return pneumatic to said first named pneumatic to assist the return movement of the first named pneumatic, said return pneumatic being energized only during the return movement of said valves. 120

10. Two valves, a pneumatic to move both said valves, and a return pneumatic and mechanical connections from said return 130

pneumatic to said first named pneumatic to assist the return movement of the first named pneumatic, said return pneumatic being energized only during the return movement of one of said valves.

11. A valve and a seat therefor, a pneumatic to move the said valve in one direction of its distance from its seat, and a return pneumatic energized by air tension to mechanically actuate the said valve in the reverse direction at every occurrence of its return, but to be always inactive when the said valve is at rest.

12. A valve and a seat therefor, a pneumatic to move the said valve in one direction of its distance from its seat, and a return pneumatic energized by air tension to mechanically actuate the said valve in the reverse direction at every occurrence of its return, but to be always inactive when the said valve is at either end of its motion.

13. A valve and a seat therefor; a pneumatic adapted to move the said valve in one direction of its distance from its seat; and a return pneumatic energized by air tension to mechanically actuate the said valve in the reverse direction but to be always inactive when the said valve is at rest.

14. A valve and a seat therefor; a pneumatic adapted to move the said valve in one direction of its distance from its seat; and a return pneumatic energized by air tension to mechanically actuate the said valve in the reverse direction but to be always inactive when the said valve is at either end of its motion.

15. Two valves; a pneumatic adapted to move both said valves, but one said valve at a time in advance of the other said valve; and a return pneumatic to assist the return of the first said valve only.

16. Two valves; a pneumatic to move both said valves; and a return pneumatic; mechanical connections from said return pneumatic to said first named pneumatic to assist the return movement of the first named pneumatic, said return pneumatic being energized only during the return movement of said first named pneumatic.

17. A valve board; two valves disposed adjacent one face of the said board and at a distance from each other; a pneumatic to move both said valves; and a return pneumatic to assist the return movement of one only of the said two valves.

18. Two valves, one having its motion independent of the other; a pneumatic means to move both said valves; and a return pneumatic to assist the return of the said first named pneumatic.

19. Two valves, one having its motion independent of the other; a pneumatic means to move both said valves, and a return pneumatic to assist the valve return movement.

20. Two valves having their motion in

different lines of action; a pneumatic to move both valves, but to move one said valve at a time in advance of the other said valve; and a return pneumatic to assist the return of the first said valve only.

21. Two valves having their motion in different lines of action; a pneumatic to move both valves, but to move one said valve at a time in advance of the other said valve; and a return pneumatic to assist the return movement of the said first named pneumatic.

22. Two valves having their motion in different lines of action; a pneumatic to move both valves, but to move one said valve at a time in advance of the other said valve; and a return pneumatic to assist the return movement of one only of the said two valves.

23. A striker pneumatic and a suction service valve and an outer air supply valve; an air chamber connected with the interior of the said pneumatic which chamber and pneumatic are alternately served with suction air and outer air by the two said valves; pneumatic means to close the said outer air valve and open the said suction air valve; and a return pneumatic to assist the return movement of the first named pneumatic means.

24. A striker pneumatic and a suction service valve and an outer air supply valve; an air chamber connected with the interior of the said pneumatic which chamber and pneumatic are alternately served with suction air and outer air by the two said valves; pneumatic means to close the said outer air valve and open the said suction air valve; and a return pneumatic to assist the return movement only of the outer air valve.

25. A striker pneumatic and a suction service valve and an outer air supply valve; an air chamber connected with the interior of the said pneumatic which chamber and pneumatic are alternately served with suction air and outer air by the two said valves; pneumatic means to close the said outer air valve and open the said suction air valve; and a return pneumatic to assist the return movement of the outer air valve.

26. A striker pneumatic and a suction service valve and an outer air supply valve; an air chamber connected with the interior of the said pneumatic which chamber and pneumatic are alternately served with suction air and outer air by the two said valves; pneumatic means to close the said outer air valve and open the said suction air valve; and a return pneumatic to assist the valve return movement only.

27. A striker pneumatic and a suction service valve and an outer air supply valve thereto; pneumatic means to close the said outer air valve and open the said suction

air valve; and a return pneumatic to assist the return movement of the outer air supply valve only.

28. A striker pneumatic and a suction service valve and an outer air supply valve connected thereto; pneumatic means to close the said outer air valve and open the said suction air valve; and a return pneumatic energized by air tension to mechanically assist every return movement of the said pneumatic means, and only said return movement.

29. A striker pneumatic and a suction service valve and an outer air supply valve connected thereto; pneumatic means to close the said outer air supply valve and open the said suction air valve; and a return pneumatic to assist the return movement only of the outer air supply valve only.

30. A striker pneumatic and a suction service valve and an outer air supply valve connected thereto; pneumatic means to close the said outer air valve and open the said suction air valve; and a return pneumatic to assist the return only of the said pneumatic means.

31. A striker pneumatic and a suction service valve and an outer air supply valve connected thereto; pneumatic means to close the said outer air valve and open the said suction air valve; and a return pneumatic to assist the return movement of one only of the said two valves.

32. A striker pneumatic and a suction service valve and an outer air supply valve; an air chamber connected with the interior of the said pneumatic, which chamber and pneumatic are alternately served with suction air and outer air by the two said valves; pneumatic means to close the said outer air valve and open the said suction air valve; a suction chamber; and a return pneumatic exposed to said suction chamber and having an air connection from the interior of the said return pneumatic to the interior of the said alternately served air chamber of the said striker pneumatic.

33. A striker pneumatic and a suction service valve and an outer air supply valve; an air chamber connected with the interior of the said pneumatic, which chamber and pneumatic are alternately served with suction air and outer air by the two said valves; pneumatic means to close the said outer air valve and open the said suction air valve; a suction chamber; and a return pneumatic exposed to said suction chamber and having an air connection from the interior of the said return pneumatic to the interior of the said alternately served air chamber of the said striker pneumatic; one of the said valves in a position to close the connection from the alternately served air chamber to the interior of the said return pneumatic at one end of the motion of the said valve.

34. A striker pneumatic and a suction service valve and an outer air supply valve; an air chamber connected with the interior of the said pneumatic, which chamber and pneumatic are alternately served with suction air and outer air by the two said valves; pneumatic means to close the said outer air valve and open the said suction air valve; a suction chamber; and a return pneumatic exposed to said suction chamber and having an air connection from the interior of the said return pneumatic to the interior of the said alternately served air chamber of the said striker pneumatic; one of the said valves in a position to close the connection from the alternately served air chamber to the interior of the said return pneumatic at that end of the motion of the said valve when the second named pneumatic is collapsed.

35. A striker pneumatic and a suction service valve and an outer air supply valve; an air chamber connected with the interior of the said pneumatic, which chamber and pneumatic are alternately served with suction air and outer air by the two said valves; pneumatic means to close the said outer air valve and open the said suction air valve; a suction chamber; and a return pneumatic exposed to said suction chamber and having an air connection from the interior of the said return pneumatic to the interior of the said alternately served air chamber of the said striker pneumatic; the said outer air supply valve in a position to close the connection from the alternately served air chamber to the interior of the said return pneumatic at one end of the motion of the said valve.

36. A striker pneumatic and a suction service valve and an outer air supply valve; an air chamber connected with the interior of the said pneumatic, which chamber and pneumatic are alternately served with suction air and outer air by the two said valves, and the two said valves disposed within said chamber; pneumatic means to close the said outer air valve and open the said suction air valve; a suction chamber; and a return pneumatic exposed to said suction chamber and having an air connection from the interior of the said return pneumatic to the interior of the said alternately served air chamber of the said striker pneumatic; the said outer air supply valve adapted to close the connection from the alternately served air chamber to the interior of the said return pneumatic at one end of the motion of the said valve.

37. A striker pneumatic and a suction service valve and an outer air supply valve; an air chamber connected with the interior of the said pneumatic, which chamber and pneumatic are alternately served with suction air and outer air by the two said valves;

pneumatic means to close the said outer air valve and open the said suction air valve; a suction chamber; and a return pneumatic exposed to said suction chamber and having 5 an air connection from the interior of the said return pneumatic to the interior of the said alternately served air chamber of the said striker pneumatic; the said outer air supply valve in a position to close the connection 10 from the alternately served air chamber to the interior of the said return pneumatic at the position of said valve when it is opened from its outer air service.

38. A striker pneumatic and a suction service valve and an outer supply valve connected thereto; pneumatic means in a position to close the said outer air valve and open the said suction air valve; a suction chamber; and a return pneumatic exposed to said suction chamber and having an air connection from the interior of the said return pneumatic to the interior of the said striker pneumatic.

39. A striker pneumatic and a suction service valve and an outer supply valve connected thereto; pneumatic means to close the said outer air valve and open the said suction air valve; a suction chamber; and a return pneumatic exposed to said suction chamber and having an air connection from the interior of the said return pneumatic to the interior of the said striker pneumatic; one of the said valves in a position to close the connection from the interior of the said striker pneumatic to the interior of the said return pneumatic at one end of the motion of the said valve.

40. A striker pneumatic and a suction service valve and an outer supply valve connected thereto; pneumatic means to close the said outer air valve and open the said suction air valve; a suction chamber; and a return pneumatic exposed to said suction chamber and having an air connection from
45 the interior of the said return pneumatic to the interior of the said striker pneumatic; one of the said valves in a position to close the connection from the interior of the said striker pneumatic to the interior of the said
50 return pneumatic at that end of the motion of the said valve when the first named pneumatic is collapsed.

41. A striking pneumatic and a suction service valve and an outer supply valve connected thereto; pneumatic means to close the said outer air valve and open the said suction air valve; a suction chamber; and a return pneumatic exposed to said suction chamber and having an air connection from the interior of the said return pneumatic to the interior of the said striker pneumatic; the said outer air supply valve in a position to close the connection from the interior of the said striker pneumatic to the interior of

the said return pneumatic at one end of the 65 motion of the said valve.

42. A striker pneumatic and a suction service valve and an outer supply valve connected thereto; pneumatic means to close the said outer air valve and open the said suction air valve; a suction chamber; and a return pneumatic exposed to said suction chamber and having an air connection from the interior of the said return pneumatic to the interior of the said striker pneumatic; one of the said valves in a position to close the connection from the interior of the said striker pneumatic to the interior of the said return pneumatic at one end of the motion of the said valve. 70 75 80

43. A striker pneumatic and a suction service valve and an outer supply valve, connected thereto; pneumatic means to close the said outer air valve and open the said suction air valve; a suction chamber; and a return pneumatic exposed to said suction chamber and having an air connection from the interior of the said return pneumatic to the interior of the said striker pneumatic; one of the said valves in a position to close the connection from the interior of the said striker pneumatic to the interior of the said return pneumatic at the position of said valve when it is opened from its outer air service. 85 90 95

44. A striker pneumatic and a suction serv-
ice valve and an outer supply valve con-
nected thereto; pneumatic means to close
the said outer air valve and open the said
suction air valve; a suction chamber; and a 100
return pneumatic exposed to said suction
chamber and having an air connection from
the interior of the said return pneumatic to
the interior of the said striker pneumatic;
an actuating rod connected to one of the 105
said valves and extended into the said suc-
tion chamber and the said valve in a pos-
ition to close the connection from the inter-
ior of the said striker pneumatic to the
interior of the said return pneumatic at one 110
end of the motion of the said valve.

45. A striker pneumatic and a suction service valve and an outer supply valve connected thereto; pneumatic means to close the said outer air valve and open the said suction air valve; a suction chamber; and a return pneumatic exposed to said suction chamber and having an air connection from the interior of the said return pneumatic to the interior of the said striker pneumatic; 115 an actuating rod connected to the said outer air supply valve and extended into the said active air service chamber, and the said valve in a position to close the connection from the interior of the said striker pneumatic to the interior of the said return pneumatic at one end of the motion of the said valve. 120 125

46. A hinged pneumatic motor having a fixed board and a moving board; a heel piece inwardly extended from one end and the inner face of the fixed board and a hinge attached to one end of the moving board and to the outer part of the end of the said heel piece; and an air channel in said heel piece extended from the outer end of the said heel piece to the interior of the pneumatic.
- 10 47. A hinged pneumatic motor having a fixed board and a moving board; a heel piece inwardly extended from one end and the inner face of the fixed board and a hinge attached to one end of the moving board and to the outer part of the end of the said heel piece; and an air channel in said heel piece extended from the outer end of the said heel piece first inwardly and then at an angle to the said first direction and then entering a part of the interior of the said pneumatic.
- 15 48. A hinged pneumatic motor having a fixed board and a moving board; a heel piece inwardly extended from one end and the inner face of the fixed board and a hinge attached to one end of the moving board and to the outer part of the end of the said heel piece; and an air channel in said heel piece extended from the outer end of the said heel piece first inwardly and then at an angle to the said first direction and then entering a part of the interior of the said pneumatic; a port at the inner end of the said air channel; and a valve to the said port.
- 20 49. A hinged pneumatic motor having a moving board and fixed board; a recess in said fixed board; a heel piece extended inwardly from one end and the inner face of the fixed board and over a part of the said recess; and a hinge attached to one end of the moving board and to the outer part of the end of the said heel piece; and an air channel in said heel piece extended from the outer end of the said heel piece to the said recess.
- 25 50. A hinged pneumatic motor having a moving board and fixed board; a recess in said fixed board; a heel piece extended inwardly from one end and the inner face of the fixed board and over a part of the said recess; and a hinge attached to one end of the moving board and to the outer part of the end of the said heel piece; and an air channel in said heel piece extended from the outer end of the said heel piece first inwardly and then at an angle to the said first direction and then entering a part of the interior of the said pneumatic.
- 30 51. A hinged pneumatic motor having a moving board and fixed board; a recess in said fixed board; a heel piece extended inwardly from one end and the inner face of the fixed board and over a part of the said recess; and a hinge attached to one end of the moving board and to the outer part of the end of the said heel piece; and an air channel in said heel piece extended from the outer end of the said heel piece first inwardly and then at an angle to the said first direction and then entering a part of the interior of the said pneumatic.
- 35 52. A pneumatic motor having a fixed board; an action member on a face of which said motor is positioned, a plate attached to an edge of said member and extended beyond said face and opposite one end of the said fixed board of said motor, a hole in the said extended part of said plate, and a pin fastened in the fixed board of said motor and freely engaged in said hole of said plate, and additional means removably securing to said member a part of the fixed board of said motor distant from said pin and opposite said face of said member.
- 40 53. A pneumatic motor having a fixed board; an action member on a face of which said motor is positioned, a plate attached to an edge of said member and extended beyond said face and opposite one end of the said fixed board of said motor, a hole in the said extended part of said plate, and a pin fastened in the fixed board of said motor and freely engaged in said hole of said plate, and a screw removably connected through said member and into said motor at a part of said motor at a distance from that part of said motor having the said pin.
- 45 54. A pneumatic motor having a fixed board; an action member on a face of which said motor is positioned, a plate attached to an edge of said member and extended beyond said face and opposite one end of the said fixed board of said motor, a hole in the said extended part of said plate, and a pin fastened in the fixed board of said motor and freely engaged in said hole of said plate, and a screw removably connected through said member and into said motor at a part of said motor at a distance from that part of said motor having the said pin, the part of said member having said screw therethrough being an extended part of less dimension in direction of said screw than the main part of the structure of which said member is a part.
- 50 55. A pneumatic motor having a fixed board; an action chest including a board at one face thereof and the said pneumatic motor positioned on the outer face of the said board; a plate attached to an edge of said board and extended beyond the said outer face of said board and opposite one end of said motor; a hole in the said extended part of said plate, and a pin fastened in the fixed board of said motor and freely

- engaged in said hole of said plate; and additional means removably securing to said board a part of said motor distant from said pin but opposite said face of said board.
56. A pneumatic motor having a fixed board; an action chest including a board at one face thereof and the said pneumatic motor positioned on the outer face of the said board; a plate attached to an edge of 10 said board and extended beyond the said outer face of said board and opposite one end of said motor; a hole in the said extended part of said plate; and a pin fastened in the fixed board of said motor and freely 15 engaged in said hole of said plate, the part of said board at its edge opposite to that having said plate extended beyond the main part of said chest and of less thickness than said main part of said chest; and a screw 20 removably connected through said second edge part of said board and into said motor at a part of said motor at a distance from that part of said motor having the said pin.
57. A pneumatic motor having a fixed
- board; an action chest including a board 25 at one face thereof and the said pneumatic motor positioned on the outer face of the said board; a plate attached to an edge of 30 said chest and extended beyond the outer face of said chest and opposite one end of the said fixed board of said motor; a hole in the said extended part of said plate, and a pin fastened in the fixed board of said 35 motor and freely engaged in said hole of said plate, the part of said board at its edge 40 opposite to that having said plate extended beyond the main part of said chest and of less thickness than said main part of said chest; and a screw removably connected through said second edge part of said board 45 and into said motor at a part of said motor at a distance from that part of said motor having the said pin.

ROBT. A. GALLY.
